EXTRUSION MACHINE

Oreste Flavio Alfredo Biginelli, Clermont-Ferrand, France

Application February 20, 1950, Serial No. 145,184

Claims priority, application France
December 23, 1949

5 Claims. (Cl. 207—6)

1

The subject of the present invention is to produce a hollow cylindrical element in the form of a case starting from a solid starting element of cylindrical shape.

The invention relates to a method for shaping tubular elements through chasing of a material from a solid starting element, comprising a step for the formation of a rough piece having a hollow shape and a lengthening step for extending the length of said piece, said method being characterized by the fact that both said steps are performed in one and the same female member playing the double part of a die for the formation of the rough piece and of a die-stock for the lengthening of said rough piece.

According to a characteristic feature of the invention in the first step the rough piece is shaped through compressing the metal of the starting element in the space provided between a stationary punch and the female element which is also stationary.

According to another characteristic feature of the invention in the second step the obtained rough piece is lengthened through imparting a relative movement to the female member with respect to the punch in order to drive the metal of said rough piece through the annular space provided between said female member and said punch.

According to another characteristic feature of the invention one and the same movable member is used for shaping the rough piece in the first step and for placing the female member with respect to the first punch and for removing the tubular element finished in the second step.

The invention also covers a machine for carrying into practice the preceding methods or similar methods, said machine being characterized by the fact that it comprises a stationary punch and an open coaxial female member with two bores, said female member being capable of engaging said punch and of moving with respect to this latter.

According to a characteristic feature of the invention the female member is combined with a rammer which is movable with respect to said female member and which can compress the metal of the starting element in the space provided between the punch and the female member.

2

According to another characteristic of the invention the female member is provided with a bore of a large diameter providing around the head of the punch a space in which the rough piece is shaped and with a bore of a smaller diameter corresponding to that of the rammer, the punch forming a piston in the bore of a large diameter and the head of said punch providing between itself and the bore of a small diameter an annular space through which the metal forced out through the piston-forming punch is extruded.

The invention also covers tubular elements such as sockets, rough pieces of shells, cases, rough pieces obtained in accordance with the preceding methods and by means of the preceding devices or similar methods and devices and characterized by:

(a) A wall of a cylindrical outer shape and of a cylindrical or conical inner shape opening toward the edges;

(b) A bottom comprising an inner relief;

(c) A bottom comprising an outer relief.

Lastly, the invention extends to the following characteristic features and to their various possible combinations:

Machines for carrying the method of the invention into practice are shown by way of examples in the accompanying drawings in which:

Figure 1 is an axial section through the machine, the rammer being moved away from the die.

Figures 2, 3, 4 are three cross-sections of said machine along lines 2—2, 3—3 and 4—4 of Figure 1.

Figure 5 is an axial section through the machine, the rammer being inserted in the die.

Figure 6 is an axial section through the machine, the rammer being removed.

Figure 7 is a section showing a detail of the extractor.

Fig. 8 is an axial section through the machine after the work of the punch.

Figure 9 is an axial section through the machine after the removal from the die.

Figure 10 is an axial section through the machine after the engagement of the case.

Figures 11 to 14 are axial sections showing different shapes of cases which can be obtained by

means of the method in accordance with the invention.

The machine shown in Figure 1 comprises the following elements.

A punch 13 secured, for example through screwing, to the stationary head 14 of the press.

Said punch comprises a cylindrical rod 13, a shoulder in the shape of a cylindrical collar 15 and, lastly, a head 16 of a shape suited to that of the case to be obtained as, for example, a frustoconical shape in the case of the example shown.

A female element 17 forming both a die and a die-stock. Said female element 17 is centered on punch 13 and secured, for example by threads 21, below a slide 18 slidably arranged on rod 13 of the punch and rigidly secured to the movable head of the press through two rods 19, 20.

The female element 17 is bored along the axis of punch 13 so as to form two different elements, an upper element 22 the diameter of which is markedly larger than the largest diameter of the head 16 of the punch and a lower element 23 the diameter of which is equal to the diameter of the case to be obtained. Both said bores are connected together through a rounded part.

This female element is surrounded, as the case may be, by a heating means 24 such as electric resistances in order to allow a working in the hot.

A rammer 25 co-axial with punch 13 and formed of a cylindrical rod 25 carrying at its upper end a head 26 the diameter of which is slightly larger than that of the rod.

Said head can slide with a sliding fit in the lower bore 23 of the female element 17.

The cylindrical rod 25 of the rammer carries on the side opposed to head 26 a cylindrical foot 27 the diameter of which is larger than that of rod 25.

The above described rammer is carried by a movable member 28 of the press.

Said movable member 28 comprises two recesses 29-30 limited on one side of a diametral plane x-x by a cylindrical surface the axis of which is that of rammer rod 25 and of punch 13 and being on the other side, freely open at the end (Figures 3 and 4).

The diameter of the cylindrical part of recess 29 corresponds, save the play, to the diameter of rod 25 of the rammer while the diameter of recess 30 corresponds to the diameter of foot 27 of said rammer.

Two washers 31-32 arranged in recess 30 on both sides of foot 27 of the rammer limit the displacements of said rammer with respect to the press member 28 and act as stops.

A handle 35 secured to the rammer makes it possible to grasp the rammer and, more particularly, to put it in position in the movable member 28 or to remove it therefrom.

A removable wedge 33 (Figure 2) in the shape of a horseshoe and provided with a handle 34 can be interposed between the head 14 of the press and the slide 18. This wedge holds fast the slide 18 which abuts downwards against the shoulder 15 of punch 13 and upwardly against said wedge 33 which itself abuts upwardly against head 14.

An extractor 36 which can be set in position in recess 30 with a large diameter of movable member 28 when rammer 25 is removed.

Said extractor 36 (Figure 6) is such that it makes it possible downwardly to introduce a cylindrical object having a diameter equal to that

of the rammer head but prevents said object to rise.

In the case of the example shown said extractor is formed of a ring 36 having an outer cylindrical surface fitted in recess 30 of the movable head and an inner frusto-conical surface 37. Independent sectors 38 are provided with a nose 39 on the inside and, on the outside, with a frusto-conical bearing surface corresponding to the inner surface 39 of ring 36. Said sectors are axially pushed upwardly through springs 40 and thus tend to come nearer axis y-y' (Figure 7) while sliding against the conical inner surface 37 of the ring.

A cylindrical piece introduced between the extractor sectors can be moved downwardly while pushing the sectors 38 away from one another but not upwardly, for said sectors are jammed between said piece and the inner conical bearing surface 37 of ring 36.

The above described machine works as follows:

The starting piece is a short length of a bar or billet 1 of a cylindrical shape. Its diameter is by a few tenths of one millimetre smaller than that of the case to be obtained.

The various working steps are the following.

(a) *Setting in position (Figure 1)*

The movable press head 28 is in its lower position.

Rammer 25 is in position in the movable head 28.

Billet 1 is placed on the head of rammer 25.

The female element 17 is locked in its lower position through the horseshoe-shaped wedge 33 inserted between slide 18 and press head 14.

When working in the hot the heating sleeve 24 is set in action and billet 1 is previously heated.

The inside of female element 17 and billet 1 are lubricated.

(b) *Formation of the rough piece (Figure 5)*

The movable press member 28 moves in the direction of arrow f¹ while carrying with it rammer 25 the head 26 of which enters bore 23 of the female element after billet 1 carried by said head.

Billet 1 is squeezed and opens on head 16 of the stationary punch and the metal is forced back around said head into the space provided between said head 16 and the upper bore 22 of the female element which then acts as a die.

At the end of the stroke of rammer 25 a rough piece 41 is obtained which surrounds head 16 of the punch and externally fits the shape of die 22.

(c) *Setting in position of the extractor (Figure 6)*

The movable member 28 is moved downwardly till a position in which rammer head 26 is released from die 17.

Rammer 25 is then removed from movable press member 28 by seizing it with its handle 35 and releasing it laterally.

Extractor 36 maintained in position through rings 31-32 is then introduced into recess 30 of the movable head 28.

Wedge 33 of the slide is then removed.

(d) *Extruding of the case (Figure 8)*

When the movable press member 28 is moved upwardly (in the direction of arrow f¹) said movable member 28 strikes with its upper face against the lower face of the female member 17 and moves said female member 17 upwardly.

During this movement the metal of the rough piece 41 which covers the stationary punch head 16 is forced back downwardly and extruded into the annular space provided between punch head 16 and the rounded edge forming the entry of the lower bore 23 of the female member 17, then between said head 16 and the lower bore 23 itself, which thus acts as a die-stock.

The case is thus formed while developing downwardly and entering the upper bore 29 of the movable head and then extending between the segments 38 of extractor 36.

This movement of the movable head 28 proceeds further till the shoulder which separates both bores 22-23 of the female member 17 comes to strike against collar 15 of the stationary punch. At this moment all the metal of the rough piece 41 has been extruded in a tubular cylindrical shape and forms the case 42.

(e) Extraction (Figures 9 and 10)

While the movable head 28 then moves downwardly in a direction according to arrow f^2 the female member 17 and the slide 18 follow this movement till said slide 18 comes to strike against collar 15 of the punch.

The head 16 of said punch is released from the end of the formed case (Figure 9).

While the movable head 18 moves further downwardly (in the direction of arrow f^2) the formed case 42 which is held by extractor 36 is drawn downwardly and is completely released from the female member 17.

It is then possible to remove the formed case 42 as well as extractor 36 out of the movable head 28 while laterally releasing them as already done for rammer 25.

Rammer 25 is then reset in position on the movable head 28 and the device is ready for another operation.

The above described method offers many technical advantages and more particularly the following.

(1) The billet which is used as the starting element has a diameter which is substantially equal to that of the case to be obtained instead of having a very large diameter as in the case of the known methods.

Said reduction in the diameter of the bar which must be divided into small lengths through sawing reduces the loss of metal due to the sawdust and, consequently, the cost of the case.

(2) In the step for the formation of the rough piece rammer 25 acts upon a billet the diameter of which is comparatively small, which requires from the press a stress which is less than in the known machines in which the rammer shapes and forces back a starting element the diameter of which is substantially larger.

The second step (formation of the case) requires a stress which is less important as that of the first step. It is thus possible, in accordance with the present invention, to use a press of less force than in the case of the known machines.

(3) When the case is completely extruded metal particles may remain in the neighbourhood of the shoulder which separates both bores 22-23 of the female member 17 but in the course of the following operation for the formation of the rough piece these particles are loosened and removed by the metal which moves upwardly while passing around head 15 of the punch and pushed back upwardly into the upper part of the annular space provided between said head 16 and the bore 22 of the female member 17.

In the course of the following extrusion operation these particles will not interfere with the extrusion nor scratch the cylindrical walls of the extruded case. They will finally be incorporated with the metal of the case edges which metal will be removed later.

(4) The volume of the billets which are cut is never rigorously constant; in the case of the method which is claimed these differences in the volume of the starting element result in a bottom which is more or less thick in the rough piece 41 without said differences of thickness giving rise to changes in the position of the punch head 16 with respect to the female member 17.

(5) The second step, the extrusion, also always occurs in the same conditions of initial position and if the bottoms may show slightly different thicknesses the inner shape of all the cases is rigorously the same from one piece to another.

(6) The case which is obtained may have a bottom of any desired thickness.

(7) If the punch head 16 is a cylindrical one the formed case will have itself a cylindrical inner shape. If the punch head is a frustoconical one the inner shape of the formed case will be slightly conical and the walls of said case will be thinner on the edge than in the neighbourhood of the bottom.

(8) Through giving a suitable relief to the lower face of the punch head 16 it will be possible to give the same relief to the inner face of the case bottom.

Likewise, a relief carried by the head 28 of rammer 25 will be reproduced on the outer face of the bottom of said case.

The above described method may be used for all metals, alloys or materials which can be shaped through a chasing operation under pressure in the cold or in the hot as, for example, brass, aluminium, light alloys, aluminium bronze, mild steel and the like.

The method may be used for making hollow elongated elements as, in most cases, cylindrical cases having a bottom, irrespective of the size of said elements, the thickness of the walls and that of the bottom.

The method in accordance with the invention may be used, more particularly, for making rough pieces for cartridge cases and shell cases.

Figures 11 to 14 are axial sections showing rough pieces for shell cases obtained with the method in accordance with the invention.

In the case of Figure 11 the cylindrical walls of the rough piece 45 have a thickness which decreases from the bottom to the edges and the bottom is smooth on both faces.

In the case of Figure 12 the bottom of the rough piece 45 is provided with a central hollow 48 on the outside and with an inner annular groove 44.

Said rough pieces make it possible through a single drawing operation after annealing to obtain the definitive shape of the case.

The manufacture of such shell cases is thus much simplified and the cost of said cases is reduced.

The method and the machines in accordance with the invention may also be used for making rough pieces for compressed gas bottles (Figures 13 and 14). They make it possible to obtain rough pieces having cylindrical walls of a very regular thickness without any part being out of centre and bottoms having a convex shape (Figure 13) or a plane shape (Figure 14) with any desired thickness.

The method may also be used for making shell

rough pieces which require no external turning operation in order to level the thicknesses of the wall owing to the very good centering of the extruded shape.

I claim:

1. In a machine for shaping tubular elements through chasing material from a solid starting element, a press with a stationary head and a movable member having a recess, a stationary punch fixed to the press head, a female member co-axial with said punch and provided with two bores of different diameters, a rammer removably mounted in the recess of the movable member of the press, said rammer being capable of compressing the metal of the starting elements in the space provided between the punch and the bore of large diameter in the female member in order to form the rough piece, means for moving the female member with respect to the punch in order to drive the metal of the rough piece through the annular space formed between the punch and the bore of smaller diameter in the female member, and an extractor capable of being removably mounted in the recess of the movable member of the press instead of the rammer.

2. In a machine for shaping tubular elements through chasing material from a solid starting element, a press with a stationary head and a movable member, said movable member comprising a recess formed of two parts and limited on the one side of a diametral plane $x-x'$, through cylindrical bearing surfaces co-axial with the rammer rod and the punch and the diameters of which are different, said parts of the recess being freely open on the outside on the other side of the diametral plane $x-x'$, a stationary punch fixed to the press head, a female member co-axial with the punch and provided with two bores of different diameters, a rammer removably mounted in the recess of the movable member of the press, said rammer being capable of compressing the metal of the starting element in the space provided between the punch and the bore of large diameter in the female member in order to form the rough piece, means for moving the female member with respect to the punch in order to drive the metal of the rough piece through the annular space provided between the punch and the bore of smaller diameter in the female member, and an extractor capable of being removably mounted in the recess of the movable member of the press instead of the rammer, the change being effected by releasing said rammer laterally through the free opening in both parts of the recess of the movable member.

3. In a machine for shaping tubular elements through chasing material from a solid starting element, a press with a stationary head and a movable member comprising a recess formed of two parts and limited on the one side of a diametral plane $x-x'$ by cylindrical bearing surfaces co-axial with the rammer rod and the punch and the diameters of which are different, both parts of said recess being freely open on the outside on the other side of the diametral plane $x-x'$, a stationary punch fast with the press head, a female member co-axial with the punch and provided with two bores of different diameters, a rammer provided with a head capable of sliding in the bore having the smaller diameter of the female member, a cylindrical rod entering the recess of small diameter in the movable member and a foot the diameter of which is larger than that of the rod and entering the recess

75

respect to the punch in order to drive the metal

of larger diameter of the movable member, said rammer being capable of compressing the metal of the starting element in the space provided between the punch and the bore of larger diameter in the female member in order to form the rough piece, means for moving the female member with respect to the punch in order to drive the metal of the rough piece through the annular space provided between the punch and the bore having a smaller diameter of the female member, and an extractor which can be removably mounted in the recess of the movable member of the press instead of the rammer, the change being effected by releasing said rammer laterally through the free opening of the recess of the movable member.

4. In a machine for shaping tubular elements through chasing material from a solid starting element, a press with a stationary head and a movable member comprising a recess formed of two parts and limited on the one side of a diametral plane $x-x'$ by cylindrical surfaces co-axial with the rammer rod and the punch and the diameters of which are different, said recess being freely open on the outside on the other side of the diametral plane $x-x'$, a punch fast with the press head, a female member co-axial with the punch and provided with two bores of different diameters, a rammer provided with a head which can slide in the bore having the smaller diameter of the female member, a cylindrical rod entering the recess having the smaller diameter of the movable member and a foot the diameter of which is larger than that of the rod and entering the recess of the larger diameter of the movable member, washers arranged in the recess having the larger diameter on both sides of the foot of the rammer, said rammer being capable of compressing the metal of the starting element in the space comprised between the punch and the bore of large diameter in the female member in order to form the rough piece, means for moving the female member with respect to the punch in order to drive the metal of the rough piece through the annular space provided between the punch and the bore having the smaller diameter in the female member, and an extractor which can be removably mounted in the recess of the movable member of the press, instead of the rammer, the change being effected by releasing the rammer laterally through the free opening of the recess of the movable member.

5. In a machine for shaping tubular elements through chasing material from a solid starting element, a press with a stationary head and a movable member, a slide which can slide on head and be moved through abutment by the movable member of the press, a stationary punch fixed to the press head and comprising a cylindrical rod secured to said head, and on which the slide slides, said punch comprising, furthermore, a collar and a head the diameter of which is smaller than that of the collar, a female member secured to the slide co-axial with the punch provided with two bores of different diameters, one of large diameter in which the collar of the punch can slide, said collar acting as a piston, and the other of larger diameter which the head of the piston can enter while providing a free annular space, a rammer fastened to the movable member of the press and capable of compressing the metal of the starting element in the space provided between the punch and the bore of large diameter in the female member in order to form the rough piece, means for moving the female member with respect to the punch in order to drive the metal

of the rough piece through the annular space provided between the punch and the bore of smaller diameter in the female member, a horse-shoe-shaped wedge provided with a handle and which can be arranged around the rod of the punch between the stationary press head and the slide fast with the female member in order to hold fast this female member with respect to press head and to the punch and to shape the rough piece.
